CLAIM

The ornamental design for a heat resistant sleeve for a descent controller, as shown and described herein.

DESCRIPTION

FIG. 1 is a front perspective view of the heat resistant sleeve; FIG. 2 is a bottom perspective view of the heat resistant sleeve;

FIG. 3 is a top view of the heat resistant sleeve;

FIG. 4 is a bottom view of the heat resistant sleeve;

FIG. 5 is a front elevation view of the heat resistant sleeve;

FIG. 6 is a rear elevation view of the heat resistant sleeve;

FIG. 7 is a right side elevation view of the heat resistant sleeve;

FIG. 8 is a left side elevation view of the heat resistant sleeve; and,

FIG. 9 is a front perspective view of the heat resistance sleeve with descent controller.

The broken lines illustrate portions of the environment and illustrate portions of the heat resistant sleeve for a descent controller. None of the broken lines form part of the claimed design.
